Inventor

Charles D. Mosher

UNITED STATES PATENT OFFICE.

CHARLES D. MOSHER, OF COOK COUNTY, ILLINOIS.

IMPROVEMENT IN PHOTOGRAPHIC SKY-LIGHTS.

Specification forming part of Letters Patent No. **137,790**, dated April 15, 1873; application filed March 9, 1872.

To all whom it may concern:

Be it known that I, CHARLES D. MOSHER, of the county of Cook, in the State of Illinois, have invented certain Improvements in the Construction and Arrangement of Adjustable Sky-Lights for Photograph and other Art Galleries, of which the following is a specification:

The first part of my invention relates to a simple and effective plan for the construction and suspension of an adjustable sky-light so that it may be placed and held in position as the operator or manager may deem requisite for the purpose of allowing light to enter the room in accordance with the position of the sun, or in such degree or at such an angle as may be desirable, with or without the use of a sun-shade, as will be shown. The second part of my invention relates to a combination, with adjustable sky-light, of adjustable and folding side pieces moving with and adapting themselves to the position of said sky-light and closing the apertures made between the roof and sky-light, as the latter is changed in position against the weather.

Reference will be had to the accompanying drawing forming part of this specification, in which Figure 1 is a side sectional view of my adjustable sky-light, showing method of suspension and "side pieces." Fig. 2 is an end view and vertical section of the same.

A is a sky-light constructed of glass set in a properly-braced frame, placed in roof B with hinge or pivot A', as shown at point 1, (see Figs. 1 and 2,) and supported at its upper end by or from upright frame C, which (C) consists of two standards, c c, from the building, and cross-beam C', Fig. 2, in the following manner: a a and b b are blocks and cable-fastenings attached to cross-beam C' at points 2 2 and to frame of sky-light at points 3 3, Fig. 2. To these blocks and cable-fastenings are attached and affixed the short wire cables d d, thus forming the connection between frame C and the frame of sky-light A: These short wire cables are spliced to the main cable D at point 4, Fig. 2, which (D) runs over rollers e and f and down to windlass E, to which it is attached, Figs. 1 and 2. To the upper corners of the frames of sky-light are attached wire cables g g, which run over rollers h h on posts c c and have weights i i suspended respectively thereto. F

is a frame of iron or other substantial material, upon which may be placed or hung a sun-shade.

To adjust the sky-light the operator, standing inside and turning at the windlass through cable D and its attachments, raises or lowers the upper end of sky-light, which swings upon hinge or pivot A' to such angle or position as he may desire. The weights i i, which are used as balances, move accordingly and give steadiness and ease of management to the operation.

For the purpose of procuring the necessary sweep to the upper end of the sky-light, and yet not protrude the same objectionably above or below the roof it is arranged that the line upon which the sky-light joins the roof may be the center of such sweep, so that it can be depressed below said line as far as it may be raised above. Hence, to close the openings to the weather, which shall be made by fixing the sky-light otherwise than at this center, adjustable folding sides, made of rubber cloth G G, Figs. 1 and 2, or other pliable and substantial material, are provided and attached to the roof and sky-light; and, in order that such cloth may keep in proper position and may fold regularly and evenly as the sky-light is raised or lowered, bars j j, forming stiffening-frames for said cloth are hinged or pivoted at point 1, so that they shall describe the same sweep as the sky-light and may fold the cloth in manner like that of the folding top of a carriage; and thus these adjustable folding sides, moving with, accommodate themselves to the position of, the sky-light, the frame of which is just enough smaller than the opening in the roof to allow a free passage below when lowered. Thus it will be seen that the operator, standing at and turning the windlass, may easily and readily adjust the sky-light at such an angle or position as he may desire, and the folding sides, adapting themselves to the motion and position of the sky-light, always protect the room from the weather as well as if the sky-light were stationary.

The sun-shade upon frame F may be used, as the operator desires, to mellow the light when the sky-light is above the center of sweep—that is, above the line where it meets the roof—or, in fact, in any position in which it may be placed.

Having thus described my invention, I claim

as new and desire to secure by Letters Patent—

1. The adjustable sky-light A, in combination with roof B, when so arranged that the upper end of said sky-light may be raised above or be depressed below the line of junction with said roof, in manner set forth.

2. The combination of upright frame C, placed upon roof B, with sky-light A, for the purpose indicated.

3. The combination of cable D, adjustable sky-light A, and upright frame C, substantially as described.

4. The windlass E and cable D, in connection with short cables d d and blocks and ca-

ble-fastenings a a and b b, for the purpose and as herein set forth.

5. The adjustable folding sides G G, when used for the purpose and in the manner described.

6. The bars j j, forming stiffening-frame for and used in combination with folding sides G G, as set forth.

To the above specification I have signed my hand this 6th day of March, 1872.

CHARLES D. MOSHER.
